(57) **CLAIM**

I claim the ornamental design for a hammer drill non-spindle lock, substantially as shown.

DESCRIPTION

FIG. 1 is a perspective view of the hammer drill non-spindle lock.

FIG. 2 is an opposite perspective view of the hammer drill non-spindle lock.

FIG. 3 is a side view of the hammer drill non-spindle lock.

FIG. 4 is top view of the hammer drill non-spindle lock.

FIG. 5 is a bottom view of the hammer drill non-spindle lock.

FIG. 6 is a front view of the hammer drill non-spindle lock; and,

FIG. 7 is a rear view of the hammer drill non-spindle lock.
